UNITED STATES PATENT OFFICE.

LOUIS R. ASH, OF KANSAS CITY, MISSOURI.

CENTER LOCK FOR BASCULE BRIDGES.

Application filed September 7, 1926. Serial No. 133,755.

My invention relates to a lock for movable bridge spans and more particularly to a device of that character for use in connection with double span bascule bridges although adaptable to bridges of single span bascule, draw or lift types, the principal objects of the invention being to lock the movable span or spans in traffic carrying position uniformly at various points in the width of the bridge, to effect the locking at the various points synchronously and to control the locking and unlocking operations from a point distant from the lock and its operating mechanism.

In accomplishing these and other objects of the invention, hereinafter mentioned, I have provided improved details of structure, the preferred forms of which are illustrated in the accompanying drawings, wherein:

Fig. 1 is a vertical section of the meeting ends of the movable spans of a bascule bridge equipped with my improved locking mechanism, the lock housing being in section to disclose the working parts.

Fig. 2 is a plan view of the meeting ends of the spans, illustrating the series of locks and their operating mechanism.

Fig. 3 is an enlarged vertical section of one of the locks in functional position.

Fig. 4 is an enlarged vertical section of the lock in non-functional position, illustrating its operating mechanism.

Fig. 5 is a detail perspective view of a locking jaw set with its actuator.

Fig. 6 is a cross section on the line 6—6 Fig. 4.

Fig. 7 is a detail perspective view of one of the lock stops.

Referring more in detail to the drawings: 1 and 2 designate the meeting ends of the spans of a double span bascule bridge, the mounting of the spans and their counter weights for maintaining the equilibrium at the different positions thereof being omitted for the reason that such parts may be of any ordinary and well known construction.

At various points throughout the width of the span 1 are stop members 3, each comprising a plate 4 fixed to one of the structural members of the span by rivets 5 or other suitable means, and a head 6, preferably integral with the plate 4 and having flat upper and lower faces projecting beyond the span for engagement by locking jaws with which the other span member is equipped.

In order to provide uniformity of contact between the locking jaws of all of the locking members and their corresponding stops, I provide each head 6 with one or more shims 7 and with wear plates 8, removable from the head for replacement when the plates have become worn and particularly when the plates on the different stop heads have worn unevenly.

For each of the stops 3 on the span 1 the span 2 is provided with a mating jaw set, each jaw set being mounted in a housing indicated by the body 9 attached to a structural member of span 2 by bolts or the like 10 and comprising top and bottom plates 11, 12 and side plate 13 (Fig. 6) spaced from the body plate 9, the body plate 9 and the spaced plate 13 having guide slots 14 and 15 at about their centers for a purpose presently described.

Carried by and extended between the body plate 9 and spaced plate 13, near the front edge of the housing and in line with the guide slots 14 and 15, is an axle 16 and mounted on the axle are jaws 17 and 18 which extend beyond the housing and past the edge of the span to grip the corresponding stops 6 on the mating span member. Each of the jaws has a countersink 19 at its rear outer corner and seated in said countersink and pivotally connected with the jaw by a pin 20 is a toggle link 22, the links on each jaw being spaced to receive therebetween the end of the mating toggle link 23 together with the toggle levers 25, the link 23 being pivotally connected with the housing plates by a pin 24, and the links 22 and 23 and the ends of the levers 25 being pivotally connected by a common pin 26. The levers 25 of the upper and lower jaws overlap and are pivotally connected by a pin 27, carrying nuts 28 on its respective ends and secured thereto by cotter keys 29. The nuts 28 are located in the guide slots 14 and 15 of the body plate 9 and spaced housing plate 13 and serve to anchor the pin and in addition to their function of retaining the toggle levers against spreading movement, serve to anchor the pin 27 and the toggle levers against vertical movement and insure travel thereof in a plane intersecting the jaw axis.

Also pivotally mounted on the toggle levers and the pin 27 is the head 30 of the toggle actuator, comprising a threaded shank 31 which extends rearwardly through a bear-

ing 32 at the rear end of the housing. Threaded onto the shank 31 is a sleeve 33 having snug bearing in the bearing 32 and keyed to the sleeve at the inner end of the bearing 32. 5 The bearing is a gear wheel 34, preferably of the worm type. A leaf 35, integral with or fixed to the housing, forms a bearing for the actuator shank forwardly of the bearing 32 and also serves as an abutment for the hub 10 of the gear wheel 34, thereby permitting the gear wheel to rotate between the end of the bearing 32 and the leaf 35 while preventing movement of the gear wheel longitudinally with the actuator shank. Meshing with the gear wheel 34 is a gear wheel 36 fixed on a shaft 37 that extends transversely across the bridge span and is rotatably mounted in suitable bearings 38 thereon. At a suitable point on the span, preferably at about the center thereof the shaft 37 is provided with a fixed gear wheel 39 which meshes with a pinion 40 on the shaft 41 of a motor 42, preferably of an electrical type. The motor may be equipped with a brake or other elements 15 in accordance with common practise and is adapted for control from a switch (not shown) that may be located at an attendant's station at the end of the bridge or otherwise.

Assuming a bascule bridge of the double span type to be equipped with locking mechanism as above described, the operation is as follows: When the bridge is in traffic carrying position, the spans align and the locking jaws of each set grip the corresponding stops on the other spans to hold the spans firmly together. When the bridge is to be opened the attendant cuts in the motor to drive the line shaft, thereby effecting rotation of the gear wheels 34 in each of the locking sets, rotation of the gear wheels carrying the sleeves 33 around with them and the sleeves working on the threaded shanks of the toggle actuators moving the toggle levers from the aligning positions indicated in Fig. 3 30 to the aligning positions indicated in Fig. 4, breaking the toggles 22, 23 and spreading the locking jaws to release the stops 6. When the jaws have been spread as described the bridge is opened. When the bridge is closed the attendant reverses the motor, straightening the toggle levers and closing the jaws against their corresponding stops.

The operation of all of the jaws of the lock units is synchronous and the locking of the spans at the spaced positions is uniform and will continue so through various succeeding operations, except that some of the wear plates on the stops might be of softer material than those on other stops and consequently deteriorate more quickly. If this should happen, uniformity of the lock may be again established by replacement of the wear plates to bring them back to gauge.

In Fig. 3, I have shown the toggle links

in a horizontal plane, but when the device is first installed, the links are broken upwardly on a slight angle so that as the stop plates wear, the toggles may straighten to closely grip the plates. With the stops all properly aligned by their wear plates and shims the jaws will close tightly and uniformly against the stops, and should the plates on any stops wear unevenly to an extent sufficient to permit looseness in the lock, such plates may be replaced and the uniformity and close contact of the jaws and stops reestablished. Should all of the plates wear uniformly, the close contact between the jaws and stops and uniformity of locking is still maintained. Should the wear reach a point where the toggle links when in a horizontal plane do not effect contact of the jaws with the stops, all the plates should be renewed.

While I have, for simplicity of description, specifically referred to the use of my improvement in connection with double span bascule bridges, it may be employed to advantage on single span bascule bridges or on other types of bridges employing movable spans or decks.

What I claim and desire to secure by Letters Patent is:—

1. In combination with separate bridge span members, one movable relative to the other, a stop on one of the members, a pair of jaws axially mounted on the other member to close against the stop, a pair of toggle links for each jaw member, one connected with the jaw member and the other with the span member, spreading levers for the toggle links, and an actuator for the spreading levers.

2. In combination with separate bridge span members, one movable relative to the other, a stop on one of the members, a pair of jaws axially mounted on the other member to close against the stop, a pair of toggle links for each jaw member, one connected with the jaw member and the other with the span member, pivotally connected spreading levers for the toggle links, an actuator for the links and means for guiding the actuator in a fixed path to effect opening and closing movement of the toggle links upon longitudinal movement of the actuator.

3. In combination with separate bridge span members, one movable relative to the other, a stop on one of the members, a pair of jaws axially mounted on the other member to close against the stop, a pair of toggle links for each jaw member, one connected with the jaw member and the other with the span member, spreading levers for the toggle links, and an actuator for the spreading levers, having a screw-threaded shank, a gear wheel operable on said shank, means for anchoring the gear wheel against movement with the actuator, and means for rotating

the gear wheel to effect longitudinal movement of the actuator.

4. In combination with separate bridge span members, one movable relative to the other, a stop on one of the members, a pair of jaws axially mounted on the other member to close against the stop, a pair of toggle links for each jaw member, one connected with the jaw member and the other with the span member, spreading levers for the toggle links, an actuator for the spreading levers, and a wear plate removably mounted in the stop member.

5. In combination with separate bridge span members, one movable relative to the other, a stop on one of the members, a pair of jaws axially mounted on the other member to close against the stop, a pair of toggle links for each jaw member, one connected with the jaw member and the other with the span member, spreading levers for the toggle links, an actuator for the spreading levers, having an extended shank, a gear wheel operable on said shank, means for anchoring the gear wheel against movement with the actuator, a gear wheel on the span member, a motor on the span member operatively connected with the last named gear wheel, and means for controlling the motor from a point remote therefrom.

6. In combination with separate bridge span members, one movable relative to the other, a plurality of stops on one of the

members, corresponding locking jaw sets on the other span member, toggle mechanism for each jaw set, an actuator for each toggle mechanism comprising a threaded shank, gear members threaded on said shank, means for anchoring the gear members against longitudinal movement with the actuator, a shaft mounted transversely on the jaw carrying span member, gear wheels fixed on said shaft and meshing with the actuator gear wheels, and means for rotating the shaft to open and close the jaw sets in synchronism.

7. A locking mechanism of the character described, comprising a housing, a pair of jaws axially mounted in the housing, a pair of toggle links for each jaw, one of the links of each pair connected with the jaw and the other with the housing, a lever for each toggle pair, an actuator comprising a head and a threaded shank, the head pivotally connected with the toggle levers, the housing having guide portions and the toggle levers provided with guide members, co-operative to insure travel of the lever axis in a fixed path, a sleeve threaded on the actuator shank, a gear wheel fixed on said sleeve, means for anchoring the sleeve and gear wheel against movement longitudinally with the actuator, and means for actuating the gear wheel.

In testimony whereof I affix my signature.

LOUIS R. ASH.
